JOHN E. BRIELMAIER, OF CHICAGO, ILLINOIS, ASSIGNOR TO THE T. F. PHILLIPS CO., OF DUBUQUE, IOWA, A CORPORATION OF IOWA.

DESIGN FOR A CONFESSIONAL PRIE-DIEU.

No. 38,277.

Specification for Design.

Patented Oct. 9, 1906.

Application filed July 30, 1906. Serial No. 328,482. Term of patent 7 years.

To all whom it may concern:

Be it known that I, JOHN E. BRIELMAIER, a citizen of the United States, residing at Chicago, in the county of Cook and State of Illinois, have invented a new, original, and ornamental Design for a Confessional Prie-Dieu, of which the following is a specification, reference being had to the accompanying drawing, forming a part thereof.

The figure is a perspective view of a confessional prie-dieu, showing my new design.

I claim—

The ornamental design for a confessional prie-dieu as shown.

JOHN E. BRIELMAIER.
